US0D1000878S

(12) **United States Design Patent** (10) Patent No.: **US D1,000,878 S**
(45) Date of Patent: ** Oct. 10, 2023

(54) **STORAGE CADDY**

(71) Applicant: **Shenzhen Ke Le Sheng Ye Technology Co., Ltd.**, Shenzhen (CN)

(72) Inventor: **Ke Zhang**, Shenzhen (CN)

(73) Assignee: **Shenzhen Ke Le Sheng Ye Technology Co., Ltd.**, Shenzhen (CN)

(**) Term: **15 Years**

(21) Appl. No.: **29/818,275**

(22) Filed: **Dec. 7, 2021**

(51) LOC (14) Cl. **06-06**

(52) U.S. Cl.

USPC **D6/683.1**

(58) **Field of Classification Search**

USPC D3/304, 307, 308, 309, 310, 311;
D6/672, 675, 675.1, 683, 683.1; D19/75,
D19/95

CPC .. B65D 1/34; B65D 5/48002; B65D 5/48024;
